METHOD AND APPARATUS FOR TREATING
PAPER STOCKEdwin Cowles, Cayuga, N. Y., assignor to The
Cowles Company, Princeton, N. J., a corpora-
tion of New Jersey

Application January 15, 1940, Serial No. 314,107

13 Claims. (Cl. 92—26)

This invention relates to methods and apparatus for treating paper stock, and pertains more particularly to method and apparatus for defibring, refining and otherwise preparing paper stock for use on paper making machines.

In a prior patent, No. 1,883,597 issued October 18, 1932, I described a method of treating paper stock in which the stock is contained in a vat, and is circulated by a pump which withdraws stock from the vat and returns it thereto, the returned stock being discharged into the vat at high velocity through submerged nozzles. The high velocity jets discharged by the nozzles exercise a defibring and refining effect on the stock due to the tearing effect of the high velocity jets moving through the relatively stationary body of stock in the vat.

Subsequently, in Patent No. 2,219,571, issued October 29, 1940, I described a different form of apparatus utilizing the principle of my aforementioned patent. In said patent, however, instead of withdrawing stock from the vat and returning it to the vat through nozzles, I provide a rotary impeller which is submerged in the vat, which said impeller is provided with open grooves so designed as to discharge high velocity jets from the rim of the impeller, which said jets have the same refining and defibring effect as the jets discharged from the nozzles in the aforementioned patent.

According to the present invention I continue to utilize the principle of refining and defibring by discharging stock at high velocity through a surrounding body of relatively stationary stock, but it is an object of the present invention to increase the efficiency of the refining and defibring action.

At the outset, it is necessary to understand that in utilizing the principle of high velocity discharge, the desired refining and defibring action takes place along the surfaces of the body of stock which is moving at high velocity, i. e. along the areas where there is a great differential in velocity. Thus, if the stock is discharged from a nozzle having a circular aperture, the refining and defibring action occurs along a cylindrical or conical surface, but the stock within the cylinder or cone receives little or no refining or defibring effect, since the stock within the cylinder or cone moves along, until its energy is spent, without being subjected to the tearing effect which occurs at the surface of the cylinder or cone.

It will also be understood that the surface area of a jet discharged from a circular nozzle of any

given aperture area may be increased by changing the shape of the aperture. Thus, a nozzle having a rectangular aperture of given area will discharge a jet having a greater surface area than a nozzle having a circular aperture of the same area, and by elongating the aperture, the surface area may be greatly increased. The difficulty is, however, that the solid components of the stock tend to clog such elongated nozzle apertures, and they cannot be used successfully in practice.

According to the present invention I propose to increase the surface area of the stock which is discharged at high velocity by discharging the same in the form of a relatively thin circular sheet, such as a relatively thin annular disk. In the preferred embodiment illustrated this is accomplished by mounting a multiplicity of vanes on the surface of an open impeller disk, adjacent the rim thereof, said vanes being relatively low and being closely spaced, so that stock is discharged at high velocity around the entire periphery of the impeller in the form of a relatively thin annular disk. The surface area of the discharged disk of stock is very great and consequently the refining and defibring effect is very rapid and efficient.

According to the present invention, I also combine the purely hydraulic refining and defibring action described above with what may be called a mechanical refining and defibring action. For this purpose, I provide the impeller vanes with knife edges, inclined, as hereinafter explained, to engage the fibers so that they slide or roll along said edge and thereby receive a mechanical rubbing action. This action, taking place at a point where the stock is being accelerated by the vanes for discharge at high velocity is particularly effective, and combined with the hydraulic action previously described provides an extremely efficient defibring and refining action.

Other objects and advantages of the invention will appear hereinafter.

A preferred embodiment of the invention selected for purposes of illustration is shown in the accompanying drawings, in which,

Figure 1 is a vertical sectional view.

Figure 2 is a plan view of a portion of the impeller.

Figure 3 is a side elevation of one of the inner impeller vanes.

Figure 4 is a top plan view of one of the outer impeller vanes.

Figure 5 is a side elevation of the same.

Figure 6 is a vertical section through the impeller.

Referring to the drawings, a vat or tank 1 is provided, preferably cylindrical in shape, which said tank may, if desired, have its side walls lined with tile 2. The bottom of the tank is provided with a sunken chamber 3, and the space between said chamber and the cylindrical side wall of the tank may be filled with concrete 4 to provide a sloping surface as illustrated in Figure 1. Such a sloping surface directs the stock discharged from the impeller, as hereinafter explained, upwardly along the side walls of the tank and assists in maintaining circulation in the stock contained in the tank as indicated by arrows in Figure 1. If desired, fixed directional vanes 5 may be embedded in the concrete to direct the stock which is discharged from the impeller in an upward direction and to restrain to some extent the circulation in a horizontal plane.

An impeller, in the form of a disk 10, is mounted in the chamber 3, and may be rotated in any suitable manner, as by pulley 11, driven by motor 12, operating through suitable reduction gears (not shown) mounted in the housing 13.

The impeller disk is provided with a multiplicity of impeller vanes 14 mounted adjacent the rim of the disk, said vanes projecting upwardly from the upper surface of the disk. The said vanes may be secured to the disk in any suitable manner, but in the embodiment illustrated, the vanes are secured, as by welding, to a ring 15 which is set into a groove 16 formed in the disk, which said ring is held in place by screws 17. Thus, the impeller is of the "open" type, being distinguished from the "closed" type impellers by the absence of any enclosures, hoods, shrouds, passages or the like which are commonly used to increase the efficiency of impellers employed for pumping or circulating purposes, but which are wholly unsuited for defibering paper stock.

In order to avoid stapling of stock on the vanes 14, the advancing face 18 of each vane is inclined to the surface of the disk, and in cases where the mechanical action referred to is desired, the face is slotted to receive a blade 19 having a knife edge 20. The knife edge is also inclined to the surface of the disk at an angle such that the fibers engaged thereby roll and slide along the edge. The angle of inclination should preferably not exceed 30° and is preferably somewhat less, as for example, the angle illustrated in the drawings is approximately 18°. The lower edge of the blade is provided with a hook portion 21 which engages a mating hook portion in the slot to hold the blade firmly in position, but to allow easy removal for replacement. Preferably the trailing end of the blade 19 extends somewhat beyond the end of the inclined face of the vane and terminates in a point 23 which has a picking action on large pieces of solid material which may be introduced into the tank. A multiplicity of such edges and points, acting successively on a large piece of solid material, operate in the manner of a saw to rapidly reduce such pieces to smaller size.

The height of the vanes above the surface of the disk is small relative to the diameter of the disk at the circumference which intersects the mid point of said vanes, and should not exceed a ratio of 1 to 30. For example, using a disk having a diameter of 5', the height of the vanes should not exceed 2", and should preferably be about 1 1/2", so that the disk of stock discharged from the impeller will be relatively thin.

The impeller should be rotated at a rate sufficient to discharge the stock at the rim of the

impeller at a velocity of at least 1000 ft. per minute and in some cases at considerably higher velocities, as for example, between 1,000 and 2,000 ft. per minute, the particular velocity selected 5 in excess of 1000 ft. per minute depending on the toughness of the stock being treated. For purposes of this specification, therefore, the term "high velocity" is defined as comprehending velocities in excess of 1000 ft. per minute, for tests 10 have shown that while some defibering action may be produced at lower velocities, it is not possible to produce completely defibered stock within the limits of practical operation. At lower velocities it has been found that defibering proceeds with reasonable rapidity until the undefibered pieces of stock reach a certain size, after 15 which the rate of defibering is rapidly reduced or defibering action may cease entirely. Even long continued treatment often fails to produce complete defibering. Using high velocities, as defined herein, however, defibering action proceeds rapidly to completion.

The mechanical action of the blades 19 has been found to be particularly effective, not only 20 in aiding the hydraulic action in defibering undefibered stock, but also in refining the defibered stock. In this connection, it will be noted that since the blades are located on the vanes, at a point where the stock is being accelerated, and 25 since the blades are inclined to the surface of the impeller disk, the fibers which are engaged thereby are subjected to a severe mechanical rubbing action both against the blades and against adjacent fibers. The effect produced on the 30 fibers in this manner is very useful, in that after defibering is complete, less subsequent treatment is required to prepare the stock for use on paper machines.

It is important to maintain proper circulation 40 of the stock at all times in order that all portions of the stock may be repeatedly subjected to the action of the impeller. The preferred type of circulation is that which is in the nature of a vortex or whirlpool comprising circulation in both horizontal and vertical planes. It has previously been stated that the sloping sections 4 of the bottom of the tank contribute to this result in directing the stock discharged from the impeller upwardly along the sides of the tank, and 45 it has also been pointed out that excessive circulation in the horizontal plane may be restrained by fixed directional vanes 5.

Another contributing feature in this connection is the relative diameters of the impeller and the tank, for it has been found that in order to maintain proper circulation, the diameter of the impeller should be greater than one fourth and 50 less than one half the diameter of the tank.

Still another contributing feature to the maintenance of proper circulation is the supplementary vanes 25 which are also mounted on the upper face of the impeller disk between the vanes 14 and the center of rotation of the impeller. The advancing face 28 of the vanes 25 may be 55 inclined to the face of the disk, as shown, to prevent pieces of stock from stapling thereon. The said vanes 25 initially accelerate the stock at the center of the impeller and move it toward the vanes 14 which additionally accelerate it and discharge it in disk form as previously described. Since the vanes 25 continually move stock away from the center of the impeller, thus drawing stock down centrally from the top of the tank, they assist greatly in maintaining the 60 vortical circulation which has been found so

highly useful in the operation of this apparatus. When the consistency of the stock is low, as at the beginning of a batch operation, the vertical cavity may extend all the way down to the impeller, so that the impeller may be seen from the top of the tank. As the consistency increases the depth of the cavity may decrease, but the vertical circulation continues, so that the undefibered portions of the stock, frequently in pieces of large size which otherwise tend to float on the surface, are drawn down into the vortex and are immediately subjected to the defibering action of the impeller.

This feature of the invention permits a method of operation hitherto unknown in the preparation of paper stock. In using the ordinary breaker beater, for example, it is necessary to feed in the solid material slowly in small batches allowing each batch to be partially defibered before introducing additional batches. Otherwise the machine becomes clogged or jammed and must be shut down. Considerable time is thus consumed in merely charging the machine, after which additional treating time is required. With the present apparatus, however, the entire charge of solid material may be introduced at one time at the beginning of the operation when the consistency is at its lowest point and the vertical action is at its maximum effectiveness. Thus, at the beginning of an operation, the required amount of water is introduced into the tank, and the required amount of solid material is introduced to produce whatever stock consistency is desired in the finished batch, as for example, from 3% to 10% consistency. As the operation proceeds, the action of the vortex is relied upon entirely to submerge the solid material and bring it into the zone of action of the impeller.

The machine particularly illustrated and described herein is intended for batch operation, but it will be understood that it may be combined with devices such as illustrated in my co-pending application Serial No. 267,804 which permit continuous withdrawal of defibered material from the chamber 3, and consequently, continuous operation of the machine. In the present machine, the chamber 3 which surrounds the impeller is provided with two drain pipes 28 and 28', controlled by valves 29 and 29' which may, if desired, be operated hydraulically by pistons 30 and 30'. Fresh water supply pipes 31 and 31' are provided for flushing out the chamber 3 after the contents of the tank have been discharged.

It will be understood that while the invention has been described herein with particular reference to the treatment of paper stock, the apparatus described and claimed herein may also be employed to advantage for many other purposes and uses. Thus, such apparatus may be used for the general purpose of disseminating, dispersing and maintaining in suspension divisible insoluble solids, and for breaking up and putting into solution solids which are soluble.

It will be understood that the invention may be variously modified and embodied within the scope of the subjoined claims.

I claim as my invention:

1. The method of pulping paper stock in batches which comprises introducing the required amount of water into a tank, introducing the entire charge of fibrous material required to produce the desired batch consistency into said tank at one time, and maintaining a vertical circulation with a hollow core in said tank where-

5 by floating solid material is submerged by the action of the vortex.

2. The method of pulping paper stock in batches which comprises introducing the required amount of water into a tank, introducing a charge of solid fibrous material into said tank at one time, said charge being sufficient to produce a stock consistency in excess of 3% in the finished stock, and maintaining a vertical circulation with a hollow core in said tank whereby floating solid material is submerged by the action of the vortex.

10 15 20 25 30 35 40 45 50 55 60 65 70 75

3. The method of pulping paper stock in batches which comprises introducing the required amount of water into a tank, introducing the entire charge of fibrous material required to produce the desired batch consistency into said tank at one time, maintaining a vertical circulation with a hollow core in said tank whereby floating solid material is submerged by the action of the vortex, and subjecting the solid fibrous material to defibering action at the bottom of said vortex.

4. The method of pulping paper stock which 25 30 35 40 45 50 55 60 65 70 75 comprises, creating a vertical circulation with a hollow core in a tank by means of a rotary impeller submerged in the tank with its axis beneath the core of the vortex, said impeller discharging stock outwardly in a direction substantially at right angles to the axis of rotation thereof and feeding and submerging light fibrous material through said core directly to said impeller.

5. Apparatus of the character described, comprising, in combination, a tank containing stock to be treated, an impeller disk mounted for rotation in said tank, said impeller having a plurality of vanes offset from its surface and freely exposed to the stock in said tank, said vanes being located substantially at the periphery of said disk, the ratio of the height of said vanes to the diameter of the disk being less than one to thirty, whereby when said impeller disk is rotated at high speed, a thin disk of high velocity stock is discharged in a direction substantially at right angles to the axis of rotation of said disk.

6. Apparatus of the character described, comprising, in combination, a tank containing stock to be treated, an impeller disk mounted for rotation in said tank, said impeller having a plurality of vanes offset from its surface and freely exposed to the stock in said tank, the ratio of the height of said vanes to the diameter of said disk at the circumference which intersects the mid point of said vanes being less than one to thirty, whereby when said impeller disk is rotated at high speed, a thin disk of high velocity stock is discharged in a direction substantially at right angles to the axis of rotation of said disk.

7. Apparatus of the character described, comprising, in combination, a tank containing stock to be treated, an impeller disk mounted for rotation in said tank, said impeller having a plurality of vanes offset from its surface and freely exposed to the stock in said tank, said vanes having impelling surfaces substantially perpendicular to the surface of said disk but inclined to a radius of the disk passing therethrough, the ratio of the height of said vanes to the diameter of said disk at the circumference where the mid point of said vanes is located being less than one to thirty, whereby when said impeller disk is rotated at high speed, a thin disk of high velocity stock is discharged in a direction sub-

stantially at right angles to the axis of rotation of said disk.

8. Apparatus of the character described, comprising, in combination, a tank containing stock to be treated, an impeller disk mounted for rotation in said tank, said impeller disk having a plurality of vanes offset from its surface and freely exposed to the stock in the tank, the ratio of the height of said vanes to the diameter of said disk at the circumference where the mid point of said vanes is located being less than one to thirty, whereby when said impeller disk is rotated at high speed, a thin disk of high velocity stock is discharged in a direction substantially at right angles to the axis of rotation of said disk, and additional means carried by said impeller disk for assisting in establishing a downward flow of stock toward the center of said impeller.

9. Apparatus of the character described, comprising, in combination, a tank containing stock to be treated, an impeller disk mounted for rotation in said tank, said impeller disk having a plurality of vanes offset from its surface and freely exposed to the stock in the tank, the ratio of the height of said vanes to the diameter of said disk at the circumference where the mid point of said vanes is located being less than one to thirty, whereby when said impeller disk is rotated at high speed, a thin disk of high velocity stock is discharged in a direction substantially at right angles to the axis of rotation of said disk, said impeller disk also being provided with additional vanes located inwardly of said first named vanes, said additional vanes being adapted to move stock outwardly toward said first named vanes.

10. Apparatus of the character described, comprising, in combination, a tank containing stock to be treated, an impeller disk mounted for rotation on a vertical axis in said tank, said impeller disk having a plurality of vanes offset from its surface and freely exposed to the stock in the tank, said vanes being relatively shallow and located substantially at the periphery of the disk, the ratio of the height of said vanes to the diameter of the disk being less than one to thirty, whereby when said impeller disk is rotated at high speed a thin disk of high velocity stock is discharged in a direction at right angles to the axis of rotation of said disk, and a vortical circulation is induced with the axis of the vortical circulation coinciding substantially with the axis of rotation of the impeller.

11. Apparatus of the character described, comprising, in combination, a tank containing stock to be treated, an impeller disk in the bottom of said tank and mounted for rotation on a vertical axis, said disk being provided with a plurality of vanes upon its upper surface and freely exposed on the upper side to the stock in said tank, said vanes being relatively shallow and located substantially at the periphery of the disk, the ratio of the height of said vanes to the diameter of the disk being less than one to thirty, whereby when said impeller disk is rotated at high speed a thin disk of high velocity stock is discharged in a direction at right angles to the axis of rotation of said disk, and a vortical circulation is induced with a hollow core of sufficient depth to feed material from the surface of the stock to the central upper surface of said impeller.

12. Apparatus of the character described, comprising, in combination, a tank, an impeller disk in the bottom of said tank and mounted for rotation on a vertical axis, said disk being provided with inner and outer sets of vanes upon its upper surface and freely exposed on the upper side to the stock in said tank, said outer vanes being relatively shallow and located substantially at the periphery of the disk, the ratio of the height of said vanes to the diameter of the disk being less than one to thirty, and said inner vanes being adapted to move stock outwardly toward said outer vanes, said vanes being so constructed and arranged that when said impeller disk is rotated at high speed a thin disk of high velocity stock is discharged in a direction at right angles to the axis of rotation of said disk, and a vortical circulation is induced with a hollow core of sufficient depth to feed material from the surface of the stock to the central upper surface of said impeller.

13. The method of pulping paper stock which comprises discharging an annular disk of stock in a substantially horizontal direction through a surrounding body of stock, maintaining a vortical circulation of the body of stock above said disk of stock with a hollow core leading downward from the surface of the stock to the center of said discharged disk of stock, so that floating fibrous material may be submerged by the action of said vortex, and subjecting the same at the bottom of the vortex to the defibering action of the discharged disk of stock.
